UNITED STATES PATENT OFFICE.

MARTIN F. KETTLER, OF HOUSTON, TEXAS, ASSIGNOR TO DOWNING PNEUMATIC WHEEL COMPANY, OF HOUSTON, TEXAS.

VEHICLE-WHEEL BUFFER.

1,173,439.

Specification of Letters Patent. Patented Feb. 29, 1916.

Original application filed February 25, 1915, Serial No. 10,500. Divided and this application filed August 20, 1915. Serial No. 46,553.

To all whom it may concern:

Be it known that I, MARTIN F. KETTLER, a citizen of the United States, residing at Houston, in the county of Harris and State 5 of Texas, have invented certain new and useful Improvements in Vehicle-Wheel Buffers, of which the following is a specification.

This invention relates to resilient wheels, 10 and more particularly to that type including a hub section, a floating rim section, and a cushion which is interposed between the sections.

In wheels of this type, it is customary to 15 employ abutment members which serve to connect the hub and rim sections for rotation in unison, and it is the aim of the present invention to provide a novel and improved construction of abutment for the 20 purpose stated.

The ordinary type of buffer above referred to is in the nature of a soft rubber sleeve which co-operates with an abutment element, as, for example, a metallic sleeve. 25 It has been found by experience that where a buffer of this type is employed and is held stationary, the constant pounding and compression to which it is subjected soon results in deterioration and hardening of 30 the rubber of which the same is composed.

It is, therefore, one aim of the present invention to provide a novel means for mounting such a buffer, which means will permit of the buffer rotating freely so that 35 different portions of its surface may be presented to the abutment element.

More specifically, the invention aims to provide for such a buffer an anti-friction mounting which will permit the buffer to 40 rotate freely without, however, subjecting the same to such wear as would be incident to the mounting of the buffer directly upon a bolt or spindle.

Briefly stated, the invention resides in 45 mounting the rubber buffer sleeve upon a sleeve preferably of anti-friction metal, which latter sleeve is in turn rotatably mounted upon a bolt or any other suitable supporting element, whereby an anti-friction bearing is afforded, and it is one object of the invention to provide novel means for securing the buffer sleeve upon the sleeve of anti-friction metal in such manner as to 50 positively provide against creeping of the

rubber buffer sleeve upon the sleeve of anti-friction metal. 55

This application constitutes a division of my co-pending application for patent on buffers for vehicle wheels, filed February 25, 1915, Serial No. 10,500. 60

In the accompanying drawings: Figure 1 is a vertical transverse sectional view through a portion of a wheel equipped with the buffer embodying the present invention. Fig. 2 is a vertical transverse sectional view 65 through the buffer. Fig. 3 is a perspective view of the buffer sleeve.

Corresponding and like parts are referred to in the following description and indicated in all the views of the accompanying drawings by the same reference characters. 70

In the drawings, the wheel, in connection with which the buffer embodying the present invention is employed, is illustrated as 75 including a hub 1, which is of the ordinary construction and which is provided with a flange 2 to which is bolted or otherwise secured a plate 3 constituting one side of a casing, within which casing the pneumatic 80 cushion and the floating spoke rim are housed. The securing bolts also serve to secure in place the usual brake drum, which is indicated by the numeral 4. Fitted upon the hub 1 and fixed for rotation therewith is 85 a bearing member comprising assembled conical sections 5 and surrounding and supported by this member is a seating member 6. As these parts constitute the subject-matter of separate applications, specific description of the same is deemed unnecessary 90 in this specification. 95

A ring nut 7 is threaded onto the hub and serves to hold the sections comprising the bearing member in place, and disposed upon the hub and against the ring nut is a plate 8 which constitutes the inner section of the other side of the casing, above referred to, the outer section being in the nature of an annular plate 9 arranged concentrically to 100 the plate 8, in the manner clearly shown in Fig. 1. A plate 10 is also fitted onto the hub, and a nut 11 is threaded onto the hub and bears against the plate 10 and serves to bind this plate against the plate 8 where-by to hold the latter plate firmly in position 105 against the nut 7.

The pneumatic cushion comprises an in-

flatable inner tube 12 and a casing 13, and this cushion is fitted to the seating member 6, in the manner shown in Fig. 1, and entirely surrounds the said member. The 5 floating spoke rim, which comprises an element of the rim section heretofore referred to, is indicated at 14 and is disposed to surround the pneumatic cushion 13. Spokes 15 radiate from the said rim 14 and support the 10 outer rim 16 which carries the tire 17. In order that the hub section comprising, generally speaking, the hub and the casing plates, may be connected with the rim section just described, a number of sleeves 18 15 are arranged at intervals within the hollow rim 14 and have their open ends secured in any suitable manner in openings formed in the side walls of the said rim. Bolts 19 are secured through the marginal portions of 20 the casing plates, and these bolts have reduced ends forming shoulders 20 which serve to properly space the said portions of the said casing plates. The portions of the bolts 19 which lie between the casing plates 25 constitute the supporting elements for the buffer members, and the sleeves 18 constitute the abutment elements.

In the form of the invention herein illustrated, the anti-friction bearing comprises 30 an inner sleeve 26 which is both internally and exteriorly cylindrical and an outer sleeve 27 which may be relatively thin and which is continuously circumferentially corrugated, the corrugations extending lengthwise thereof. The soft rubber sleeve is indicated by the numeral 28 and in vulcanizing the same upon the sleeve 27, the rubber will be forced into the corrugations and some of 35 the rubber will enter or be forced through 40 perforations 29 which are formed in the corrugated surface of the sleeve 27, thereby providing for a more firm anchorage of the rubber sleeve on the said sleeve 27.

It will be understood that the anti-friction 45 sleeve is freely rotatable upon the bolt 19 or any other support which may be provided and that, consequently, different portions of the surface of the soft rubber buffer sleeve will be successively presented to the 50 wall of the abutment sleeve 18. It will further be apparent that the rubber sleeve is not directly mounted upon the bolt or other supporting element and, consequently no portion 55 of the surface of the said rubber sleeve is subjected to rubbing contact and, even should there be a relative shifting of the buffer sleeve and abutment sleeve after the two have initially been brought into contact with each other, no rubbing action will occur 60 inasmuch as the buffer sleeve as a whole, or more specifically the sleeve 26 is freely rotatable upon the anti-friction bearing. It will

further be understood that the sleeve 27 may be readily removed from the sleeve 26 when the rubber buffer sleeve has become worn 65 and it is desired to substitute a new one.

Having thus described the invention, what is claimed as new is:

1. In a wheel of the class described, a hub section and a rim section, a cushion interposed between the sections, a buffer carried by one section and including a rotatable sleeve, a corrugated sleeve fitted thereon, a yieldable sleeve surrounding the corrugated sleeve, and an abutment carried by the other 70 section for coöperation with the buffer.

2. In a wheel of the class described, a hub section and a rim section, a cushion interposed between the sections, a buffer carried by one section and including a rotatable 80 sleeve of anti-friction material, a corrugated sleeve removably fitted thereon and formed with perforations, a sleeve of yieldable material surrounding the corrugated sleeve and the said material of the yieldable sleeve entering the said perforations in the corrugated sleeve, and an abutment carried by the other section for coöperation with the buffer.

3. In a wheel of the class described, a hub section and a rim section, a cushion interposed between the sections, a buffer carried by one section and including a rotatable sleeve, a corrugated sleeve removably fitted thereon, a yieldable sleeve surrounding the 95 corrugated sleeve, and an abutment carried by the other section for coöperation with the buffer the corrugations of the second mentioned sleeve extending longitudinally of the said sleeve.

4. In a wheel of the class described, a hub section and a rim section, a cushion interposed between the sections, a buffer carried by one section and including a rotatable sleeve, a sleeve fitted thereon and having an 105 irregular exterior surface, a yieldable sleeve surrounding the second mentioned sleeve and interiorly conforming to the outer surface, and an abutment carried by the outer section for coöperation with the buffer.

5. A wheel buffer of the class described, comprising a sleeve interiorly cylindrical, a corrugated sleeve fitted thereon, and a yieldable sleeve surrounding the corrugated sleeve.

6. A wheel buffer of the class described, comprising a sleeve interiorly cylindrical, a corrugated perforated sleeve removably fitted thereon, and a sleeve of yieldable material surrounding the corrugated sleeve, the 120 material of the yieldable sleeve entering the said perforations in the corrugated sleeve.

In testimony whereof I affix my signature.
MARTIN F. KETTLER. [L. S.]
